O. BERGER.
LUBRICATOR FOR ELEVATOR GUIDES.
APPLICATION FILED MAR. 21, 1913.

Patented July 7, 1914.

UNITED STATES PATENT OFFICE.

OTTO BERGER, OF NEW YORK, N. Y.

LUBRICATOR FOR ELEVATOR-GUIDES.

1,102,641.

Specification of Letters Patent.

Patented July 7, 1914.

Application filed March 21, 1913. Serial No. 755,829.

To all whom it may concern:

Be it known that I, OTTO BERGER, a citizen of the United States, and a resident of New York, borough of Manhattan, in the county of New York and State of New York, have made and invented certain new and useful Improvements in Lubricators for Elevator-Guides, of which the following is a specification.

10 My invention relates to lubricating devices for applying oil to elevator guides, and more particularly to lubricating devices of the general type disclosed in Letters Patent No. 1,007,422 granted to me upon the 31st day of October, 1911, wherein a lubricant is applied to the guides by means of a wiper moving in contact therewith, and which wiper is supplied with oil from an oil well through or by means of a 20 tubular oil feeding member containing a wick; and, among the objects of my invention are to provide a lubricating device having oil applying means separate from the wiper; to provide a lubricating device in 25 which the upper end of the oil well is open, as distinguished from those covered by elements of the oil applying means; to provide a lubricating device in which the quantity or amount of oil supplied to the guides may be 30 easily adjusted to suit the necessities of any particular case; to provide a lubricating device which will be simple in form, and which may be readily and cheaply manufactured; and to provide such other and further improvements in and relating to lubricating 35 devices for elevator guides as are herein-after more specifically referred to.

With the objects of invention above enumerated in view, my invention consists in 40 the improved lubricating device for elevator guides illustrated in the accompanying drawing and hereinafter described and modified, and in such variations and modifications thereof as will be obvious to those 45 skilled in the art to which my invention relates.

In the drawing accompanying and forming a part of this application and wherein the preferred embodiment of my invention is illustrated: Figure 1 is a view showing a section of my improved lubricating device taken upon a vertical plane indicated by the line 1—1, Fig. 2, and illustrating how the same may be secured to an element of the 50 elevator with which it is used; Fig. 2 is a view showing my improved lubricating de-

vice in plan; Fig. 3, is a view showing a section taken upon a transverse horizontal plane indicated by the line 3—3, Fig. 1, looking down; Fig. 4 is a view showing a 60 section taken upon a vertical plane indicated by the line 4—4, Fig. 3; Fig. 5 is a fragmentary view illustrating a modified form of one of the elements of my device; and Fig. 6 is a view showing the clamping 65 and supporting means for attaching the lubricator to an elevator.

Referring to the drawing the reference numeral 8 designates a portion of a vertically extending elevator guide, and 9 a 70 portion of an elevator, to which a barrel 10 is secured and within which a spring 11 is located, which spring acts to force a shoe 12 toward and keep it in contact with the guide, all as is common in elevator structures and to which features my invention 75 in no way relates.

My improved lubricating device will be supported from the elevator so as to travel therewith by means of any suitable and appropriate bracket or equivalent supporting means, the bracket or support illustrated comprising an upwardly extending bar 13 the lower end of which rests upon and is secured to two clips 14 the lower ends of 80 which clips are curved to embrace the barrel 10, and the upper end of which bar is 85 bent downward and serves as the immediate support for my improved lubricating device.

My improved lubricating device comprises 90 a reservoir 15 adapted to contain a considerable quantity of oil as indicated in the drawing, and which oil reservoir is shown as rectangular in cross-section, although the particular form or shape of the oil reservoir 95 is of secondary importance and is not involved in my invention. The oil reservoir is adapted to support a swab 16 of absorbent material and a wiper 17 also of absorbent material, said elements being independent 100 of one another and spaced apart as shown. The swab is kept saturated or moistened with oil, and the purpose thereof is to apply lubricant to the elevator guide with which it moves in contact, while the wiper serves 105 to distribute the lubricant uniformly over the guides, and to scrape off excess lubricant and dirt should any collect upon the guide.

The swab 16 and wiper 17 are shown as 110 located within two recessed extending portions or extensions 18, 19 having upwardly

- extending peripheral or side walls as shown, and the bottom walls of which extensions are provided each with a slot adapted to receive an elevator guide as illustrated in 5 the drawing. The upper of these extensions is shown as formed integrally with the wall of the oil reservoir 15, while the lower is shown as formed separate from the reservoir and as secured thereto by a screw 20.
- 10 Either or both of said extensions may however, obviously, be formed integrally with the reservoir 15, or either or both of them may be formed separate therefrom and secured thereto in any way.
- 15 The extension 18 is preferably provided with an upwardly projecting wall or ledge 21, of less height than the side walls of and extending around the slot formed in the bottom wall of said extension, whereby an 20 oil retaining space or pocket is provided in the lower portion of said extension. There is thus a considerable quantity of oil present immediately beneath the swab 16 when the lubricator is in use, whereby the swab is 25 kept saturated with oil or sufficiently moist to secure a proper supply of oil to the elevator guide, as it will be understood that a portion of the swab extends downward and into the oil as best shown in Fig. 4. A block 30 of felt 22 is also preferably provided with which the wiper is in contact, as shown, which block serves as an additional means for keeping the swab in a saturated condition or sufficiently moistened with oil to secure 35 adequate lubrication of the elevator guide.
- The swab above referred to will obviously be of a form appropriate to apply oil to the particular form of elevator guide to be lubricated, and the form of my invention 40 illustrated in the drawing shows two such swabs arranged to apply oil to opposite faces of an elevator guide. The swabs are shown as resting upon the upper end of the ledge 45 21 and blocks of felt 22, and as held in place by plates 23 made preferably of indurated fiber, through which bolts 24 extend. The wiper 17 is also obviously of such a form as to contact with and wipe the surface or 50 surfaces of the elevator guide to be lubricated, as will be understood, and is held in place within the extension 19 by means of plates 25, also preferably of indurated fiber, and bolts 26 extending through the bottom wall 55 of the extension and through said plates. Additional plates 27, also of indurated fiber are also placed beneath the wiper 17 in order to support the lower surface of the wiper beyond the walls of the extension and close 60 to the elevator guide with which it moves in contact. The wiper 17 is made preferably of felt, although other materials may be used so long as the wiper performs its intended function of removing surplus oil 65 from the surfaces to which it is applied.

Oil is supplied to the swab 16 through or by means of an oil feeding member comprising a tube within which an absorbent material is contained, one end of which tube depends into the oil within the reservoir 15 70 and the other end of which extends to and terminates adjacent the swab, so that oil will pass along the absorbent material and through the tube and to the swab; the absorbent material being preferably in the form of a wick as shown in the drawing, and the lower end thereof extending into the oil receptacle or pocket provided in the lower portion of the extension 18.

The tubular member above referred to is 80 shown as U-shaped in form and as having a leg 28 depending into the oil reservoir, and a second leg 29 extending through a hole in the bottom wall of the extension 19 and terminating adjacent the swab 16. The upper end of this oil feeding member thus lies above the level of the oil in the oil reservoir, and the ends of the absorbent member or wick 30 thereof extend beyond the lower ends of the legs, and into the oil in the oil 90 reservoir, and into the oil retaining space or pocket formed in the lower portion of the extension 18 by the ledge 21, as hereinbefore explained. The oil feeding member is 95 preferably provided with a spring 31, the free upper end of which may be pressed against the wick, by means of a screw 32, to thereby regulate the quantity of oil passing along the wick to the swab.

My improved lubricating device is shown 100 as provided with two separate oil feeding members, in order to secure a more uniform and satisfactory supply of oil to the swabs 16, although it will be understood that a single oil feeding member will supply oil to the oil retaining pocket at the lower end of the extension 18 and consequently, to both the swabs 16.

While I have shown the oil feeding members as comprising each a single tube with a single wick therein, I prefer to make the oil feeding members in the manner illustrated in Fig. 5 wherein the same is shown as made up of a plurality of separate tubes 33, each of which contains a wick 34, and which tubes collectively form a single oil feeding member equivalent in function to one of the two oil feeding members with which my device is shown as provided in the other figures of the drawing. With this form of oil feeding member a closer and more satisfactory control of the supply of oil may be secured; as, if the supply is insufficient an additional tube may be added, while if the supply is too profuse a tube may be removed; it being understood that a plurality of these separate tubes will be necessary in order to secure an adequate supply of oil to the swabs in all cases, and that such supply may be increased or decreased by small 110 115 120 125 130

amounts if found necessary, by the addition or removal of a separate tube.

The oil reservoir is preferably provided with a splash plate 35, and with a cover 36, to prevent the oil from spilling from the reservoir and the entry of dirt thereinto.

Having thus described and explained my invention, I claim and desire to secure by Letters Patent:

1. In a lubricating device for elevator guides, an oil reservoir; a swab of absorbent material carried by said reservoir and adapted to contact with a guide to be lubricated; a wiper of absorbent material independent of and located above said swab and carried by said reservoir; a tubular U-shaped oil feeding member the upper end of which lies above the level of oil in said reservoir and one leg of which depends thereinto, and the other leg of which member terminates adjacent said swab; and a wick of absorbent material within said oil feeding member and through which oil is supplied to said swab.
2. In a lubricating device for elevator guides, an oil reservoir having two recessed extensions provided each with a slot in its bottom wall, and which slots are adapted to receive an elevator guide; a swab of absorbent material located in one of said extensions and adapted to contact with the guide; a wiper of absorbent material located within the other of said extensions and adapted to contact with the guide; a tubular U-shaped oil feeding member, the upper end of which lies above the level of oil in said reservoir and one leg of which depends thereinto, and the other leg of which member terminates adjacent said swab; and a wick of absorbent material within said oil feeding member and through which oil is supplied to said swab.
3. In a lubricating device for elevator guides, an oil reservoir having two recessed extensions provided each with a slot in its bottom wall, and which slots are adapted to receive an elevator guide; a swab of absorbent material located in the lower of said extensions and adapted to contact with the guide; a wiper of absorbent material located within the upper of said extensions and adapted to contact with the guide; a tubular U-shaped oil feeding member, the upper end of which lies above the level of oil in said reservoir, and one leg of which depends thereinto, and the other leg of which member extends through the upper of said extensions and terminates adjacent said swab; and a wick of absorbent material within said oil feeding member and through which oil is supplied to said swab.
4. In a lubricating device for elevator guides, an oil reservoir having two recessed extensions provided each with a slot in its bottom wall, and which slots are adapted to receive an elevator guide; an upwardly projecting ledge extending about the slot in the bottom wall of the lower of said extensions whereby an oil retaining space is provided in the lower portion of said extension; a swab of absorbent material located within said lower extension and adapted to contact with the guide; a wiper of absorbent material located within the other of said extensions and adapted to contact with the guide; a tubular U-shaped oil feeding member, the upper end of which lies above the level of oil in said reservoir and one leg of which depends thereinto, and the other leg of which member terminates adjacent said swab; and a wick of absorbent material within said oil feeding member and through which oil is supplied to said swab.
5. In a lubricating device for elevator guides, an oil reservoir having two recessed extensions provided each with a slot in its bottom wall, and which slots are adapted to receive an elevator guide; an upwardly projecting ledge extending about the slot in the bottom wall of one of said extensions, whereby an oil retaining space is provided in the lower portion of said extension; a swab of absorbent material located within said last mentioned extension and adapted to contact with the guide; a wiper of absorbent material located within the other of said extensions, and adapted to contact with the guide; a tubular oil feeding member one end of which depends into said reservoir and the other end of which terminates adjacent said swab; and a wick of absorbent material within said oil feeding member and through which oil is supplied to said swab.
6. In a lubricating device for elevator guides, an oil reservoir having two recessed extensions provided each with a slot in its bottom wall, and which slots are adapted to receive an elevator guide; an upwardly projecting ledge extending about the slot in the bottom wall of one of said extensions whereby an oil retaining space is provided in the lower portion of said extension; a swab of absorbent material located within said last mentioned extension, and adapted to contact with the guide; a wiper of absorbent material located within the other of said extensions and adapted to contact with the guide; a tubular U-shaped oil feeding member, the upper end of which lies above the level of oil in said reservoir and one leg of which depends thereinto, and the other leg of which member terminates adjacent said swab; and a wick of absorbent material within said oil feeding member and through which oil is supplied to said swab.
7. In a lubricating device for elevator guides, an oil reservoir having two recessed extensions provided each with a slot in its bottom wall, and which slots are adapted to receive an elevator guide; an upwardly projecting ledge extending about the slot in the bottom wall of the lower of said extensions whereby an oil retaining space is provided in the lower portion of said extension; a swab of absorbent material located within said lower extension and adapted to contact with the guide; a wiper of absorbent material located within the other of said extensions, and adapted to contact with the guide; a tubular U-shaped oil feeding member, the upper end of which lies above the level of oil in said reservoir and one leg of which depends thereinto, and the other leg of which member terminates adjacent said swab; and a wick of absorbent material within said oil feeding member and through which oil is supplied to said swab.

tact with the guide; a wiper of absorbent material located within the upper of said extensions, and adapted to contact with the guide; a tubular U-shaped oil feeding member the upper end of which lies above the level of oil in said reservoir and one leg to which depends thereinto, and the other leg of which member extends through the upper of said extensions and terminates adjacent 10 said swab; and a wick of absorbent ma-

terial within said oil feeding member and through which oil is supplied to said swab.

Signed at New York, borough of Manhattan, in the county of New York and State of New York, this 20th day of March, 1913.

OTTO BERGER.
